UNITED STATES PATENT OFFICE.

ISAAC WILLIAM PLEASANT BUCHANAN, OF LEBANON, TENNESSEE.

LAWN-SPRINKLER.

SPECIFICATION forming part of Letters Patent No. 586,161, dated July 13, 1897.

Application filed August 10, 1896. Serial No. 602,315. (No model.)

To all whom it may concern:

Be it known that I, ISAAC WILLIAM PLEASANT BUCHANAN, a resident of Lebanon, in the county of Wilson and State of Tennessee, have 5 invented certain new and useful Improvements in Lawn-Sprinklers; and I do hereby declare the following to be a full, clear, and exact description of the invention, such as will enable others skilled in the art to which 10 it appertains to make and use the same.

My invention relates to an improvement in lawn-sprinklers, the object of the invention being to construct a lawn-sprinkler which shall be automatic in operation and by means 15 of which a considerable area can be watered effectually and in a comparatively short space of time.

A further object is to produce a sprinkler, which shall be simple in construction, by 20 means of which a large quantity of water can be evenly distributed over a correspondingly large area of ground, said sprinkler being so constructed as to be ornamental in appearance and effectual in all respects in the performance of its functions.

With these objects in view the invention consists in certain novel features of construction and combinations and arrangements of parts, as hereinafter set forth, and pointed 30 out in the claims.

In the accompanying drawings, Figure 1 is an elevation of a structure embodying my invention. Figs. 2, 3, and 4 are views showing different positions which the parts assume 35 during the operation of the apparatus. Fig. 5 is a view of a modification, and Fig. 6 is a detail view.

A represents a frame, which may be made of metallic rods or tubing and may also, if 40 desired, be nickel-plated or otherwise ornamented. The base portion of the frame or stand A comprises three legs 1 2 3, united at their upper ends to the corners of a triangular frame 4. The leg 3 will preferably be 45 made in two sections normally secured together by means of a suitable clamp 5, whereby said leg can be adjusted as to length so as to permit the apparatus to stand level when used on uneven ground.

50 A triangular frame 6 is disposed below the frame 4 and secured at its corners to the legs 1 2 3. The body portion of the stand com-

prises three upright rods or bars 9 10, secured at their lower ends to the corners of the triangular frame 4 and having secured to their upper ends a ring B, of hard metal, such as steel, the rods or bars 9 being preferably continuations of the legs 1 2. The bar or upright 10 may be made somewhat larger than the bars or uprights 9 and is made with a vertical slot 12 for the accommodation of the screw of a clamp 13. This clamp comprises a plate a, disposed against the bar or upright 10, a post b, projecting from said plate, clamping-arms 15, projecting from said post and adapted to receive and hold a hose-pipe 14, a screw c', passing through the slot 12 in the bar or upright 10 and entering said plate, and a shoulder d' on said screw to bear against the outer face of the bar or upright 10. The 70 ring B is made in its upper edge with a groove g, in which an endless series of ratchet-teeth h are located, the height of these teeth being somewhat less than the depth of the groove g.

Upon the ring B a movable device which 75 for convenience I will term a "rotator" is disposed. The rotator C comprises in its structure a rectangular frame 16, supported on said ring by means of arms c d e f. The frame 16 is preferably of such size that its 80 longest diameter will be about one-half the diameter of the ring B, and at each end said rectangular frame is provided with collars 18, having angular openings, and through said collars a transverse bar 19 is adapted to 85 pass loosely. The transverse bar 19 is provided between its ends with a ring 20, through which the hose-pipe is adapted to pass. Stops 21 22 are attached to the arms c d and adapted to engage the inner face of the ring B, said 90 stops being preferably made adjustable. Stops 22 23 are adjustably attached to the arms e f and are normally disposed on said arms at points intermediate of the ring B and the rectangular frame 16. A collar i is loosely 95 mounted on each arm c d and prevented from lateral displacement by the walls of the groove g. From each collar i a dog j projects and engages the ratchet-teeth h.

The hose 14 is passed up through the ring 100 20 of the rotator, which is of such diameter as to permit the hose to pass through it loosely, so as to avoid any binding between said hose and ring. The hose will be pulled

through the ring 20 until the nozzle at the end of said hose will be about one foot (more or less) from the ring. The clamp 13 will be made to grasp the hose. When the hose has been thus attached to the apparatus, the free or nozzle end thereof will hang loosely over the top of the stand or frame A. Should the water-supply be now turned on, the frictional contact of the water against the curved free end of the hose will cause it to rise. The force of the water which thus caused the free end of the hose to rise will also cause it to move backwardly, this backward movement being permitted by the sliding transverse rod 10 or bar 19. When the bar 19 reaches the end of its movement, the ring in the center thereof will strike the end of the rectangular frame 16, and by the jar thus caused the free end of the hose will be thrown over, as indicated by dotted lines in Fig. 1. The jar caused by the engagement of the ring 20 with the end of the rectangular frame will also cause said frame to move on one of the stops or pins 21 as a pivot until the adjustable stop 22 or 23 engages the ring B. By this time the free end of the hose will have completed its oscillatory movement in the arc of a circle and will be thrown back by the action of the force of the water in the same manner as above explained, but now a new portion of the ground will be watered, as the rectangular frame 16 has made a portion of a revolution. This action of the apparatus will continue, the nozzle end of the hose oscillating back and forth in the arc of a circle and the rectangular frame making a slight movement at each oscillation of the end of the hose, until the frame 16 has made a complete revolution and a circular path of ground has been watered. By providing the ratchet device above described all lost motion when the rotator turns on the pivot pins or stops will be prevented. Without the ratchet device little irregularities of trend or flexibility of the hose-pipe would tend to interfere with perfect rotation of the rotator, but with said ratchet devices the operation of the rotator will be uniform regardless of the irregularities above mentioned. I have demonstrated by actual experiment that by means of my improved apparatus I am enabled to thoroughly water a very large area of ground in a comparatively short space of time. It will be observed that the movements of the hose are above the clamp 13, and this clamp is made adjustable, as above explained, to accommodate the apparatus to hose-pipes of different degrees of flexibility and different pressures of water. In order to insure the accurate operation of the devices above described, at the upper end of the stand the apparatus should be level, and for this purpose one of the legs is made adjustable, as above described. When it is desired to water a rectangular piece of ground, the stops 22 23 will be moved

out on the arms e f until they engage the ring B, so as to prevent the rotation of the rectangular frame 16.

The hose-pipe used may be flexible throughout or it may be made of flexible and rigid sections, if desired.

Where the pressure is more severe than ordinary the free or nozzle end of the hose-pipe might vibrate so rapidly as to cause unnecessary friction, the full throw of the hose-pipe would not be utilized and the diameter of the watered area would be shortened. To insure the proper vibration of the nozzle end of the hose-pipe under varying pressures of water, I prefer to adjustably attach a weight 26 to said hose-pipe between the rotator C and the nozzle.

Instead of the transverse sliding bar 19, above described, the rectangular frame 16 may be made with an elongated slot 27, in which the hose can move back and forth, as shown in Fig. 5

My improvements are simple in construction, comprise few parts, are ornamental in appearance, will operate to distribute water thoroughly over a large area, and are effectual in all respects in the performance of their functions.

Various slight changes might be made in the details of construction of my invention without departing from the spirit thereof or limiting its scope, and hence I do not wish to limit myself to the precise details of construction herein set forth.

Having fully described my invention, what I claim as new, and desire to secure by Letters Patent, is:

1. The combination with a frame or stand, of a device loosely mounted thereon, and a hose connected at a point near its nozzle end to said device, said hose having a rotary and rectilinear sliding motion relative to the frame or stand induced by the action of the water passing through the hose, substantially as set forth.

2. The combination with a stand, of a horizontal frame mounted thereon, said horizontal frame being constructed to receive a hose and the latter having a sliding connection therewith in such manner as to permit a transverse movement of said hose due to the pressure of the water flowing therethrough, substantially as set forth.

3. The combination with a stand and a hose, of a frame mounted thereon and a transversely-movable bar mounted in said frame and adapted to receive the hose and move in rectilinear direction, whereby the pressure of water flowing through said hose will cause said bar to move and the free end of the hose to be thrown over in the arc of a circle, substantially as set forth.

4. The combination with a stand and a hose, of a frame mounted thereon, a transversely-movable bar mounted in said frame and adapted to move automatically, and a ring between the ends of said bar for the reception

of the hose, whereby the pressure of the water passing through said hose will cause the free end thereof to rise and the transverse bar to move until said ring engages the end 5 of the frame, substantially as and for the purpose set forth.

5. The combination with a stand, of a frame, arms projecting from said frame and resting on the top of the stand, said frame being 10 adapted to receive a hose in such manner as to permit it to have a transverse movement and stops on said arms, said stops being so constructed and arranged that when the hose moves transversely and engages the end of 15 the frame, the jar thus caused will effect a partial rotation of the frame on one of said stops as a fulcrum, substantially as set forth.

6. The combination with a stand, of a horizontal frame thereon, arms projecting from 20 said horizontal frame and resting on the top of the stand, a transversely-movable device on said frame adapted to receive a hose, stops on diametrically opposite arms adapted to engage the top of the stand, and stops on the 25 other diametrically opposite arms and adapted to be made to engage said top of the stand when said horizontal frame is moved, substantially as set forth.

7. The combination with a stand, of a horizontal frame, arms projecting from said frame, 30 adjustable stops or pins on said arms and adapted to engage said horizontal frame and a reciprocating device mounted in said frame and adapted to receive a hose-pipe, substantially as set forth.

8. The combination with a stand, of a ring thereon having ratchet-teeth, a frame adapted 35 to receive a hose, arms projecting from said frame and supported on said ring, dogs carried by some of said arms and adapted to engage said ratchet-teeth, and pins or stops on said arms and adapted to engage the ring, substantially as set forth.

9. The combination with a stand, of a movable frame supported thereby, a hose-pipe 40 connected with said frame whereby to cause it to reciprocate and rotate when water is

passed through said hose-pipe, and an adjustable weight on the hose-pipe between said movable frame and the nozzle end of the hose- 50 pipe, substantially as set forth.

10. The combination with a series of vertical rods or uprights, of a ring at the upper ends of said rods or uprights, a horizontal frame, arms projecting from said frame and resting on said ring, stops on said arms, a transversely-movable bar mounted in said frame, and a ring between the ends of said bar for the reception of a hose, substantially 55 as set forth.

11. In a sprinkler, the combination with a series of uprights, of a ring at the upper ends thereof, a triangular frame below said uprights, and a rotator mounted on the ring at the tops of the uprights, for the reception of 60 said hose, substantially as set forth.

12. The combination with a stand, of a rotator mounted on said stand and adapted to receive the hose, and a clamp adapted to receive the hose below the rotator, substantially 65 as set forth.

13. The combination with a stand, of a rotator mounted on the stand and adapted to receive the hose and a hose-clamp adapted to receive the hose below the rotator, said clamp 70 being adjustably connected with the stand, substantially as set forth.

14. The combination with a stand comprising a series of uprights, one of said uprights having an elongated slot, of a rotator mounted 75 on the stand and adapted to receive a hose passing through the stand, a clamp to receive the hose below said rotator, and a screw adapted to pass through the slotted upright and enter the body of the clamp and having 80 a shoulder to bear against said upright, substantially as set forth.

In testimony whereof I have signed this specification in the presence of two subscribing witnesses.

ISAAC WILLIAM PLEASANT BUCHANAN.
